Primary Examiner — Ian Simmons*Assistant Examiner* — Keith Frank*(74) Attorney, Agent, or Firm* — The Webb Law Firm(57) **CLAIM**

The ornamental design for a container for beverages or food, as shown and described.

DESCRIPTION

FIG. 1 is an upper left front perspective view of a container for beverages or food showing my new design;

FIG. 2 is a front view thereof;

FIG. 3 is a right side view thereof;

FIG. 4 is a rear view thereof;

FIG. 5 is a top view thereof; and,

FIG. 6 is a bottom view thereof.

The broken lines in the drawings showing the container for beverages or food illustrate the portions of the container for beverages or food that form no part of the claimed design. The solid lines shown in FIG. 6 represent the boundaries between the claimed and unclaimed portions of the container for beverages or food.
